UNITED STATES PATENT OFFICE.

REMUS D. HALE, OF TRANSITVILLE, INDIANA.

IMPROVEMENT IN WHIFFLETREES.

Specification forming part of Letters Patent No. 172,266, dated January 18, 1876; application filed July 3, 1875.

To all whom it may concern:

Be it known that I, REMUS D. HALE, of Transitville, Tippecanoe county, Indiana, have invented a new and Improved Whiffletree Attachment, of which the following is a specification:

My invention consists of a dovetail-shaped projection on the under side of the whiffletree sliding into a corresponding groove in the top of a stud pivoted in the evener, and fastening by a snap-spring, so as to be easily and quickly connected and disconnected.

Figure 1 is side elevation of the evener and whiffletree. Fig. 2 is a top view, and Fig. 3 is a transverse section taken on the line $x-x$, Fig. 1.

Similar letters of reference indicate corresponding parts.

A is the whiffletree; B, the dovetailed projection which slides into a corresponding groove in the top of the stud C, which is pivoted to the evener D, and E is the fastening-spring, which snaps into a socket in the bot-

tom of the groove of the stud, so as to prevent the whiffletree from working out. The spring has a finger-pin, F, by which to lift it out of the notch when the whiffletree is to be detached.

The dovetailed projection slides in the groove from the back of the evener, so that the draft tends to keep it in place.

Having thus described my invention, I claim as new and desire to secure by Letters Patent—

1. The whiffletree connected to the evener by the dovetailed projection B and correspondingly-notched swivel-studs C, substantially as specified.
2. The combination of the snap-spring E with the dovetailed projection D and the grooved stud C, substantially as specified.

REMUS D. HALE.
